MOSES T. BURBANK, OF LAWRENCE, MASSACHUSETTS.

Letters Patent No. 88,842, dated April 13, 1869.

IMPROVED EXTENSION-LADDER.

The Schedule referred to in these Letters Patent and making part of the same.

To all whom it may concern:

Be it known that I, MOSES T. BURBANK, of Lawrence, in the county of Essex, and State of Massachusetts, have invented a new and improved "Extension-Ladder," and I do hereby declare the following to be a full, clear, and exact description thereof, reference being had to the accompanying drawings, making a part of this specification, in which—

Figure 1 is an elevation of a ladder embodying my improvements;

Figure 2 is a transverse section of a part of the same; and

Figure 3 is a detailed view of end of rail.

The object of my invention is to produce a ladder which can be extended to suit different heights to be reached, without detriment to its strength and stiffness, and by supporting the same by extension-braces, thus securing a safe, strong, and durable ladder, which will not be likely to be thrown over, either by a wrong adjustment, accidentally, or by the effect of wind; and the object is also to facilitate the storage of the ladder, which, when taken apart, occupies but little room; and

My invention consists in forming a ladder in pieces of equal length, and attaching to the outside of the rails plates, by means of bolts, and metal plates and bolts, and said plates breaking joints in the middle of the rails; and

It consists further, in providing two or more braces, each being composed of two lengths of strips of wood, breaking, also, joints in the middle of each strip, and being bolted together or otherwise secured, these braces being attached to the ladder by means of ropes, or otherwise, so as to allow a free bracing in the desired direction, and an easy attaching and adjusting to the ladder.

Referring to the drawings, A is a ladder, composed of the short ladders a a, b b, and plates c c, the latter being attached to the rails b b by washers and bolts d d, and where two ends of either rails or plates meet, by plates e and bolts f f.

It will be observed that the upper and lower plates

c c are of only one-half the length of the intermediate ones, for the reason that it is desirable to make all the rest of uniform length.

g g are the braces, composed each of two sets of pieces, breaking joints in the middle, and firmly bolted together, and provided at their upper ends with an iron strap and ring, through which the rope passes for attaching the brace to the ladder.

The ends of the rails and plates are scarfed down and rounded, for the purpose of receiving a band, h, which latter protects the ends from injury.

If it is required to use a short ladder, a portion of the ladder is taken off, as shown in fig. 1, leaving the lower end for the required length of ladder, with one-half the plates c c projecting beyond.

The braces g g have also to be shortened, and attached to a convenient place of the ladder.

Care must be taken to fill up the projecting end with a spare piece of one-half the length of a piece comprising the brace.

If a long ladder is needed, then put as many rails, plates, and brace-pieces on as will be found necessary.

As all these pieces have to be cut and fitted after a pattern, all the bolt-holes will come in their respective places, and any of the pieces will fit for the other.

Thus it will be seen, that a ladder of great usefulness, and adapted to extension, may be produced with little work and inconvenience.

What I claim as new, and desire to secure by Letters Patent, is—

The ladder A, composed of parts b c, framed and connected, as described, and supported by braces g g, of similar construction.

In testimony whereof, I have signed my name to this specification, in the presence of two subscribing witnesses:

MOSES T. BURBANK.
